BUMPER ENGAGING VEHICLE PARKING GUIDE

Jack Mendelsohn, 108-49 63rd Ave.,
Forest Hills, N.Y. 11375

Filed July 31, 1974, Ser. No. 493,703

Term of patent 14 years

Int. Cl. D10—06

U.S. Cl. D10—109

FIG. 2

FIG. 1

FIG. 4

FIG. 3

FIG. 1 is a perspective view of a bumper engaging vehicle parking guide from the front showing my new design;

FIG. 2 is a side elevation view thereof on an enlarged scale;

FIG. 3 is a rear elevation view as seen from the left in FIG. 2 on an enlarged scale; and

FIG. 4 is a bottom plan view thereof on an enlarged scale.

The wire supporting the top circular element is broken away in FIGS. 2 and 3 for convenience of illustration.

I claim:

The ornamental design for a bumper engaging vehicle parking guide, as shown and described.
